UNITED STATES PATENT OFFICE.

WALTER C. HARLOW, OF BROOKLYN, NEW YORK, AND HERBERT L. TOWLE, OF GLENDALE, PENNSYLVANIA.

DOOR-KNOB.

1,103,963.

Specification of Letters Patent. Patented July 21, 1914.

Application filed May 26, 1913. Serial No. 770,020.

To all whom it may concern:

Be it known that we, (1) WALTER C. HARLOW and (2) HERBERT L. TOWLE, citizens of the United States, residing at (1) 5 Brooklyn and (2) Glenside, in the counties of (1) Kings and (2) Montgomery and States of (1) New York and (2) Pennsylvania, have invented certain new and useful Improvements in Door-Knobs, of which 10 the following is a specification.

Our invention relates to door knobs having a very thin exterior metal shell, and relying for structural strength on a filling of suitable cement or composition, which supports the shell and affords, in conjunction with certain other parts to be described, means for connecting the shell and the central squared spindle together, and one of the objects of our invention is to provide 15 means for adjusting accurately the length of the spindle between the knobs to the thickness of the door, without using the washers ordinarily employed for this purpose.

Another object is to render it impossible to remove the outer knob, when applied to an outside door, except by first removing the inner knob.

Further objects are to simplify and 20 cheapen the processes of manufacture and increase the strength of the knob to resist rough usage.

We attain these results by means of the structures shown in the drawings which accompany this specification, in which—

Figure 1 shows in section one knob of a pair constructed according to our invention. This knob is designed more particularly for use on the outer side of a door, since it 25 cannot be removed except by first removing the knob from the inner end of the spindle. Fig. 2 shows the other knob of a pair constructed according to our invention. This may be removed from the spindle with the aid of a screw driver, and is designed more particularly as a companion knob to that shown in Fig. 1, and for interior locations generally. Fig. 3 shows an enlarged view 30 of an interiorly threaded sleeve forming part of the knob shown in Fig. 1. Fig. 4

shows an enlarged view of a two-part casting which surrounds the sleeve shown in Fig. 3. A portion of one part of the casting is broken away to indicate the form more clearly. Fig. 5 shows a wrench or 55 spanner suitable for use in turning the sleeve shown in Fig. 3. Fig. 6 shows an enlarged view of a tubular supporting piece forming part of the knob shown in Fig. 2. Fig. 7 is an enlarged perspective view of 60 a channel shaped stiffening piece, also forming part of the knob shown in Fig. 2. Fig. 8 shows a modified structure of the channel piece, which may take the place of the two pieces shown in Figs. 6 and 7. Fig. 9 is a 65 section showing the channel piece of Fig. 8, in place.

Similar letters refer to similar parts throughout the several views.

In Fig. 1, A indicates the knob, and B 70 the spindle. The metal shell of the knob is conveniently formed in two parts, a crown shell "a" and a neck shell "a'", and is interiorly supported by a mass a^2 of some suitable cement or composition, such as oxy- 75 chlorid of magnesia, which is introduced in a plastic state into the shells a and a' separately, after which said shells are united as shown or in any other convenient manner, and the cement is permitted to harden. 80

The square spindle B has a screw thread cut on its edges, giving it the properties of a screw without wholly destroying the squareness of its section.

Fitting the threads on spindle B is an interiorly threaded sleeve c , (Fig. 3) having on its inner end a flange c' , and in its outer end one or more notches c^2 , the engagement whereof with a suitable spanner enables the sleeve c to be turned. This sleeve c is 85 inclosed by a stiffening frame or casing, in which it is sufficiently loose to turn freely without unnecessary play, as shown in Fig. 4. Said casing is composed of a cylinder d having a radial flange d' at its inner end 90 provided with an annular wall d^2 , together with a cap portion d^3 having a central aperture to receive the spindle B, and adapted to fit over the annular wall d^2 at the cylinder end. The said casing is introduced into the 95 100

mass a^2 while the latter is plastic, and after the mass a^2 hardens the casing cannot be removed.

The shell a' is cut away circularly at a^3 5 to approximately the diameter of the body of the sleeve c , permitting the latter to be rotated by engaging the notches c^2 c^2 with a spanner.

In the center of the mass a^2 is a cavity or 10 axial recess a^4 , substantially square in cross section and adapted to receive the end of the square spindle B , preventing the spindle from rotating. This cavity is of a depth along its axis sufficient to allow of any required adjustment of the spindle B , to suit 15 the thickness of the door.

From the foregoing description it will be clear that the spindle B is introduced into the knob by presenting it to the end of the 20 sleeve c , and rotating the latter to draw the spindle in; also that when the spindle has been drawn in so far as to enter the square cavity a^4 , the knob cannot turn about said spindle, whereby all relative motion between 25 the knob A and the spindle B is prevented.

The spanner for turning the sleeve c may be of any suitable form. That shown at C , Fig. 5, has projections c^3 to engage the 30 notches c^2 , and is operated by slipping it over the spindle, the other knob of the pair being removed.

The other knob of the pair, shown at D in Fig. 2, is secured on the spindle by the conventional screw passing through the neck 35 of the knob into the spindle, but it embodies certain improvements made necessary by the thinness of the metal shell and the character of the cement filling, which are designed to 40 give it the strength needed to resist rough usage. In the figure, a , a' indicate the bipart members of the shell, as before, and a^2 the cement filling.

B' indicates the spindle, which may be the 45 other end of the spindle used in the knob A . Instead of having screw threads cut on its edges, it has one or more holes b' b' drilled and tapped to receive a screw E . The pressure of this screw, which tends to crush the 50 shell and cement between its head and the spindle B' , is supported by a tubular piece e , countersunk at its outer end to fit the shell where the latter is countersunk under the head of the screw. This piece e might bear 55 directly against the spindle, but we prefer to have it bear against a metal stiffening frame or channel F , which incloses the spindle on three sides and has an aperture to receive screw E . This piece F serves three 60 functions: It retains the support e in place, so that the latter cannot drop out if by any chance it works loose from the surrounding cement; it gives a smooth metal surface to three sides of the hole that receives the spin-

dle, thereby facilitating the process of manufacture; and it contributes to the strength and stiffness of the neck of the knob. 65

To facilitate still further the process of manufacture, we prefer to raise a rim f around the aperture through which the 70 screw passes, and swage the support e tightly on this rim, thus making the pieces e and F practically integral for the purpose of assembling.

The members e and F may be stamped in 75 one piece, and a suitable form thereof is shown in Fig. 8, wherein the channel F' has the annular wall f' integrally formed about the aperture, to act as a support in the same manner as the support e . Evidently, also, 80 the form of the channel may undergo various modifications without departing from the spirit of our invention. For example, its sides might be narrower than shown, or they might be extended and bent over so as 85 to inclose the fourth side of the spindle as well as the other three sides.

It will be understood that we do not limit our invention so as to exclude such departures from the exact forms shown as may be 90 made without departing from the spirit of our invention.

In attaching this door-knob to the door, the spindle B is adjusted in the knob A until the screw E in the knob D accurately 95 registers with one of the openings b' . By then screwing this screw into the spindle B , both knobs are held in proper relation.

We claim:

1. A door-knob composed of a shell of 100 thin material, a plastic filling therefor, a stiffening frame in the neck of the door knob and embedded in said filling, an internally threaded member inclosed by said knob and rotatable in said frame but held 105 against longitudinal movement, a threaded spindle in said threaded member, and means independent of said frame for preventing relative rotation of the spindle and knob.

2. A door-knob composed of a shell of 110 thin material, a plastic filling therefor, a tubular casing placed in the neck of the door knob and embedded in said filling, an interiorly threaded sleeve inclosed by said knob and rotatably fitted within said casing, 115 and a spindle having screw threads upon its edges and engaged thereby within said sleeve.

3. In a door-knob, in combination, a shell comprising a co-operating crown shell and 120 neck shell, a plastic filling therefor supporting and securing said shells rigidly together, said filling being axially recessed, a spindle having screw threads upon its edges and entered within said recess, an 125 interiorly threaded sleeve about said spindle, a casing for said sleeve permitting rotary movement but preventing longitudinal

- movement of the latter, said casing being embedded in and secured by said filling and means for turning said sleeve to advance or return the spindle.
- 5 4. A door-knob composed of a shell of thin material, a plastic filling therefor, a stiffening frame in the neck of the knob, said filling securely uniting the shell and the frame, a spindle passing through said frame,
- 10 and a screw-threaded element coöperating with the frame and spindle for securing said spindle against longitudinal movement in said frame.

In testimony whereof, we affix our signatures in presence of two witnesses.
